UNITED STATES PATENT OFFICE

ALFRED WILLIAM GEORGE TUCKER, OF HOLLINWOOD, ENGLAND, ASSIGNOR TO FERRANTI, LIMITED, OF HOLLINWOOD, LANCASTER, ENGLAND

ELECTRIC SWITCH

Application filed December 21, 1923, Serial No. 682,103, and in Great Britain January 6, 1923.

This invention relates to electric switches and more particularly to electric switch devices (termed hereinafter "tapping switches") for use in association with electric 5 transformers to effect connection to alternative tapping point windings. Actuation of such switches to change the tapping connections is usually effected subsequently to the winding controlled thereby being rendered "dead" (by some form of isolating switch) and it is a practically essential feature that means be provided whereby the tapping switch cannot inadvertently be left in such a position that connection to the 10 transformer winding remains broken.

The invention consists briefly in an electric switch including a series of contacts mounted upon a base, a longitudinally displaceable and rotatable contact blade, means constantly urging said blade towards said contacts and means ensuring correct registration between the contact blade and the fixed contacts.

Referring to the accompanying diagrammatic drawings:—

Figure 1 represents a longitudinal sectional view of a convenient construction of tap switch for single phase use;

Figure 2 is a lateral sectional view thereof; Figures 3 and 4 are views similar to Figures 1 and 2 respectively of a modified construction;

Figures 5, 6 and 7 represent respectively elevational, longitudinal sectional and lateral sectional views of a further modification for three-phase use.

The invention will now be described in one form as illustrated in Figures 1 to 3 applied by way of example to a tapping switch for a 40 three-phase transformer.

A circular base *a* of insulating material is provided and furnished with, say, six equidistantly spaced fixed contact fingers *b*, the contacts of any adjacent pair being capable 45 of being connected together at will by means of a movable connection described below.

This movable connection comprises two contact fingers *c*, *c*, disposed radially and carried rigidly upon a spider *d*, the latter being 50 slidably and rotatably supported upon a cen-

tral stub spindle *e* secured to the switch base *a*. Concentric with the stub spindle is an hexagonal cup-shaped member *m*, rigidly secured to the base, this member being slotted longitudinally so as to constitute six pillars 55 standing outwards from the face of the base.

The spider is formed with two diametral radial lugs of such width as to slide within any opposite pair of slots in the cup *m* and the strong compression spring *k* serves constantly to urge the spider *d* towards the cup *m*. The cup *m* is so positioned relatively to the fixed contacts *b* which lie around it that when the spider and cup lie together the bridging contact blades *c*, *c* rest in contact with an adjacent pair of contact fingers. The ends of the spider lugs which lie facing the fixed contacts *b*, *b* and the corresponding ends of the cup pillars are bevelled to form blunt knife edges for reasons explained below. The spider *d* is connected mechanically to an operating handle *g* by means of a tube *f* of insulating material, e. g., by means of split collars *n* and tangential clamping bolts *o*.

Certain of the contacts *b* are coupled to various tapping points on a transformer so that in order to change the tapping it is merely necessary to remove the padlock *p* securing the hinged handle cover *q*, to pull 70 out the handle *g* to rotate and then to release the same.

The cover *q* cannot be closed and padlocked until the switch has been closed completely; thus if by any chance the spring strength 80 should weaken or the contact surfaces become roughened the effect of closing the cover ensures that the switch is pushed into full engagement. A safe indication that the switch is closed at any time is thus afforded by observation of the cover *q*.

The blunt knife edges referred to prevent the switch being left in an "open" condition and ensure correct alignment between the contact fingers *c*, *c* and the fixed contacts *b*, *b*; the knife edge surfaces are mutually inclined at an angle of about 90°.

According to the modification illustrated in Figures 3 and 4 a similar construction is depicted except that in this case a central con- 100

tact r is provided in permanent electrical connection with a spider carrying a single contact arm s .

In many cases, for example when (in order to reduce the length of the necessary connections) the switch base is disposed adjacent the centre of a vertical oil-cooled transformer and the operating handle is disposed upon the upon the top of the casing, it is found desirable to interpose between the operating handle and the length of insulating tube secured to the spider an operating shaft h (Figure 1) bearing on each of its ends a universal joint j (Figure 1); this avoids the necessity for exact alignment of the axes of the operating handle and stub spindle.

It will be noted with reference to Figures 1 and 3 that not until the spider has been withdrawn practically to its fullest extent, i. e. 20 with its lugs carried beyond the extremities of the cup pillars, can the handle be rotated.

Any number of switches may be employed and in the case, say, of a three-phase transformer three switches operated simultaneously from a common point may be provided.

According to an example of this arrangement illustrated in Figures 5 to 7, three switches are mounted with their axes in line and provided with universal joints between 30 each switch and between the top switch and an operating handle. Thus a single operating handle g effects simultaneous movement of the three switch spiders d in this case. Obviously, a single compression or tension 35 spring k of sufficient strength may be employed instead of three separate springs.

The switch contact bases a, a, a in this case are mounted upon tubes w, w, w , of metal or of insulating material which are secured to 40 bosses x, x, x . These bosses are swivelably mounted between cheeks y, y, y , carried on pillars z, z, z , so that the spider spindles and locating cups m, m, m , are rendered self-aligning.

45 In order to effect the necessary longitudinal movement of the switch spiders prior to their rotation a lever t in addition to the torsion handle g may be provided, this lever acting upon a collar u borne by the operating handle spindle v .

It will be understood that according to this invention the actual changing of connections by the switch involves merely a longitudinal movement of the operating spindle 55 (to overcome the spring pressure) and then a rotary movement of the spindle to select the required connection, followed finally by a release and longitudinal return movement of the operating spindle.

60 Having now described my invention what I claim as new and desire to secure by a Letters Patent is:—

An electric switch including a series of contacts mounted upon a base, a spindle, a 65 longitudinally displaceable and rotatable

contact blade mounted thereon, means constantly urging said blade towards said contacts, a slotted cup secured to said base and constituting a bushing for said spindle, means ensuring a correct registration between the contact blade and the fixed contacts and a swivelable mounting for said base providing a self-alignment between the spindle carrying the contact blade and said cup.

In testimony whereof I have signed my name to this specification.

ALFRED WILLIAM GEORGE TUCKER.
